UNITED STATES PATENT OFFICE.

ERNEST KIRCHHOFF, OF NEW YORK, N. Y., ASSIGNOR TO PACIFIC MILLS, OF BOSTON, MASSACHUSETTS, A CORPORATION OF MASSACHUSETTS.

DESIGN FOR TEXTILE FABRIC OR WALL-PAPER.

42,213.

Specification for Design.

Patented Feb. 27, 1912.

Application filed December 14, 1911. Serial No. 665,810. Term of patent 3½ years.

To all whom it may concern:

Be it known that I, ERNEST KIRCHHOFF, a citizen of the Republic of France, residing at No. 106 East Eighty-second street, in the city, county, and State of New York, have invented a new, original, and ornamental Design for Textile Fabrics or Wall-Papers, of which the following is a specification, reference being had to the accompanying drawing, forming part thereof.

The drawing is a plan view of a portion of a textile fabric or wall paper showing my design.

I claim:

The ornamental design for a textile fabric or wall paper as shown.

ERNEST KIRCHHOFF.

Witnesses:

PHILIP F. WICKSEL,
WILLIAM F. MEEHAN.
